Atty.

UNITED STATES PATENT OFFICE.

PAUL GELINSKI, OF CLEARING, ILLINOIS.

TACK-PULLER.

1,189,090.

Specification of Letters Patent. Patented June 27, 1916.

Application filed March 2, 1916. Serial No. 81,610.

To all whom it may concern:

Be it known that I, PAUL GELINSKI, a subject of the Emperor of Germany, residing at Clearing in the county of Cook and

5 State of Illinois, have invented certain new and useful Improvements in Tack-Pullers, of which the following is a specification.

My invention relates to devices for pulling tacks or the like and more particularly 10 to devices of this character which are manipulated by hand.

The objects of my invention are to produce an exceedingly simple, cheap and durable device and to so construct the same 15 that the tack or other fastener is first loosened by a leverage movement and then drawn out by a straight and direct pull. These and other objects I accomplish as hereinafter set forth in the following description and as particularly pointed out in the appended claim, reference being had to the accompanying drawings in which an embodiment of my invention is shown.

Figure 1 represents my improved device 25 in side elevation and at a slight angle from the perpendicular with its slotted extremity slipped upon the head of a tack or the like preparatory to pulling it. Fig. 2, represents the device tilted from the position shown in Fig. 1, to a perpendicular position and with the tack or the like loosened and also showing in dotted line the device raised by a direct pull and the tack removed. Fig. 3, is an end elevation of the device. Fig. 4, 35 is a bottom view of the device.

In referring to the embodiment of my invention shown in the accompanying drawings in detail, like numerals designate corresponding parts.

40 My improved device is designed to extract or pull tacks and other fasteners with a minimum of exertion and without bending or injuring the tack or fastener. The embodiment shown is in the form of a single bar of suitable metal, such for instance as steel, having a handle 1, and a head 2, located at one end of the handle.

The head 2, is of a peculiar form, being provided with a flat end surface or face 3, which extends obliquely or at an angle which is slightly greater than a right angle to the general direction of the bar and a slot 4,

cut from one side to nearly the opposite side thereof and extending inwardly at a slight diverging angle to the face 3, see 5 Figs. 1 and 2.

From this construction it will be noted that a thin plate 5 is formed on the outer end of the head which is provided with a central V-shaped recess 6, and constitutes a 6 forked or bifurcated pulling claw which fits between the enlarged head of a tack 7, and a support 8, into which it is driven as shown in Fig. 1.

The corner 9 of the head on its unslotted 6 side is rounded and forms, as it were, a rolling fulcrum upon which the device is first tilted to loosen the fastener before it is drawn completely out.

The operation of my improved device is 7 approximately as follows:—The bifurcated claw is first fitted beneath the head of a fastener such as a tack as shown in Fig. 1. The device is now tilted or turned from the position shown in Fig. 1, to the position shown in Fig. 2 rolling on the corner 9, and elevating and loosening the fastener. The bar is then finally given a pull or jerk upward in a vertical direction thereby removing the fastener by force exerted in a 8 straight upward direction and without bending or injuring the same. The upward movement of the device is illustrated in dotted lines in Fig. 2.

While I have illustrated and described a 8 preferred form of construction for carrying this invention into effect, the same is capable of a wide range of variations, alterations, modifications and changes without departing from the spirit of the invention. I therefore do not wish to be limited to the above described form, but desire to avail myself of all such variations, alterations, modifications and changes as fairly fall within the scope of the appended claim or 9 may be construed to come within the scope of the same by involving the doctrine of equivalents.

What I claim as my invention and desire to secure by Letters Patent is:—

A tool of the class described, comprising a solid straight handle, a head at one end of said handle provided with a flat end surface which extends at an angle slightly

greater than a right angle to the general direction of the handle and a slot cut from one side to nearly the opposite side thereof and extending inwardly at a slight diverging angle to the end surface, the corner of the head on its unslotted side being rounded to constitute a rolling fulcrum and a flat

thin plate being formed by said slot on the end of the head which is recessed to form a pulling claw.

In testimony whereof, I have hereunto affixed my hand.

Chicago, Illinois, February 29, A. D. 1916.
PAUL GELINSKI.
